(57) **CLAIM**

The ornamental design for an assembly of screen and attached extension holder for remote handling and drain oil narrowing stream for removing an oil filter, as shown and described.

DESCRIPTION

FIG. 1 is a top plan view of an assembly of screen and attached extension holder for remote handling and drain oil narrowing stream for removing an oil filter, showing my design;

FIG. 2 is a right side elevation view thereof;

FIG. 3 is a bottom plan view thereof;

FIG. 4 is a front elevation view thereof; and,

FIG. 5 is a rear elevation view thereof.
